CLAIM

The ornamental design for an electric dry shaver, as shown and described.

DESCRIPTION

FIG. 1 is a front elevational view of the electric dry shaver showing my new design;

FIG. 2 is a side elevational view thereof, the opposite side being a mirror image thereof;

FIG. 3 is a rear elevational view thereof;

FIG. 4 is a top plan view thereof;

FIG. 5 is a bottom plan view thereof; and,

FIG. 6 is a front elevational view of a second modified embodiment, the portions not shown being identical to those of the first disclosed embodiment.

FIG. 4

FIG. 1

FIG. 2

FIG. 3

FIG. 5

FIG. 6
